UNITED STATES PATENT OFFICE.

JOHN K. KAHOOKANO, OF RAWLINS, WYOMING.

DESIGN FOR A TOBACCO PIPE.

Application filed October 19, 1921. Serial No. 508,883. Term of patent 3½ years.

To all whom it may concern:

Be it known that I, JOHN K. KAHOOKANO, a citizen of the United States, residing at Rawlins, in the county of Carbon and State of Wyoming, have invented a new, original, and ornamental Design for a Tobacco Pipe, of which the following is a specification, reference being had to the accompanying drawing, forming part thereof.

The figure is a side elevation of the tobacco pipe.

I claim:—

The ornamental design for a tobacco pipe, as shown.

JOHN K. KAHOOKANO.
